UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed June 11, 1929. Serial No. 370,027.

This invention relates to an improvement in a shoe form more particularly in one of the toe form type used for the purpose of plumping out the material forming the toe 5 of the shoe and bringing it into a condition which simulates the one it assumes when on the human foot.

The primary object of this invention is to provide a toe form of the expansible type 10 with means for rigidly securing the form in the expanded condition in the position which it is desired that it occupy in the shoe. A further object of this invention is to provide a toe form having side walls and a cross brace 15 for expanding said side walls, which brace has adjacent one side wall a sprag or spur by which the toe form is secured into position in the shoe. Other objects will appear to one skilled in the art from an examination of the 20 following specification taken in connection with the drawings which form a part thereof, and in which

Fig. 1 is a plan view with parts broken away of a toe form embodying this invention; and

Fig. 2 is an enlarged sectional view illustrating the construction of the toe form and particularly the means for holding the form rigidly in position in the shoe.

The toe form embodying this invention 25 comprises a body 10 having a pair of side walls 11 which terminate in inwardly projecting flanges 12. In one of the flanges 12 is provided a hole 13, while in the other is provided an arcuate slot 14. Pivottally mounted 30 in the hole 13 of the flange 12 is one end of a cross brace 15, the other end of the brace entering the slot 14 so that the side walls 11 are thereby connected. The brace 15 is preferably a length of wire provided at each end 35 with a reversely bent portion or loop 16. The end 17 of the brace 15 is again bent outwardly and then downwardly terminating in an integral vertical post 18 which enters the hole 13. The other end 19 of the brace 15 is bent 40 first outwardly, then back upon itself, forming the loop 20 and then downwardly terminating in a post 21 which engages the slot 14. It will be noted that the end 19 is coiled at 45 22 to supplement the natural resiliency of the

wire and insure that the post 21 projects downwardly through the loop 16, and projects below the loop as shown in Fig. 2. The tip of the post 21 is sharpened so that it will 55 act as a spur to hold the form in the shoe.

The method of using this shoe form will now be described briefly. The form 10 is placed in the collapsed condition shown in Fig. 1 and the post 21 preferably raised slightly in order that the tip will not project 60 below the body of the cross wire 15, as shown in Fig. 2. After being inserted in the toe of the shoe to the full extent with the side wall at the left, as shown in Fig. 1, in contact with the material forming the body of the shoe, the 65 right end of the brace 15 will then be pushed about the post 18 as a pivot, the post 21 sliding in the slot 14 until the toe form has attained the desired position and the toe of the shoe is properly plumped out. The post 21 is then 70 released and its tip enters the surface of the insole of the shoe. The form 10 is thus secured in the toe of the shoe, not only by the fact it has been expanded to the dotted line 75 position of Fig. 1 and therefore has a frictional contact with the body of the shoe, but by the tip of the post 21 which prevents the unwanted retraction of the toe member from the toe of the shoe.

The post 21 is preferably raised by the use 80 of a screwdriver or similar means inserted between the loop 20 and the upper face of the flange 12, or the post may be raised by the use of a wedge similarly inserted which remains in position until the toe form has been clearly 85 and squarely located.

It will be noted that the loops 16 of the cross wire 15 form a support for the toe member and that the pointed tip of the post 21 extends below the body of the cross brace, and 90 thus, as shown, functions as a spur or sprag. The post 18 might be similarly extended to project below the loop 16, as indicated in dotted lines on Fig. 2, and be provided with a pointed tip if it be desired to provide positive means for securing the form in the shoe 95 at both sides.

While one embodiment of this invention has been shown and described and another embodiment alluded to briefly, it will be un- 100

derstood that applicant is not limited thereto since other embodiments could be made without departing from the spirit and scope of the invention as set forth in the following claims.

I claim:

5. 1. In a hollow toe form adapted to be inserted in the toe of a shoe and having side walls, a cross brace connecting said walls, the brace being pivotally mounted upon one side wall and having a sliding engagement with the other side wall and a spur carried by said cross brace for engaging the insole of the shoe and securing the form in position therein.
15. 2. In a hollow toe form adapted to be inserted in the toe of a shoe and having side walls, a cross brace connecting said walls, the brace being pivotally mounted upon one side wall and having a sliding engagement with the other side wall and a spur carried by said cross brace for engaging yieldably the body of the shoe and securing the form in position therein.
25. 3. In a hollow toe form adapted to be inserted in the toe of a shoe and having side walls, a cross brace connecting said walls, the brace being pivotally mounted upon one side wall and having a sliding engagement with the other side wall to cause the expansion or contraction of the walls by its pivotal movement and a spur carried by said cross brace for engaging the insole of the shoe and securing the form in the shoe with the walls the desired distance apart.
35. 4. In a hollow toe form adapted to be inserted in the toe of a shoe and having side walls which terminate in inwardly projecting flanges, a cross brace connecting said walls, the brace being pivotally mounted upon the flange of one wall and having a sliding engagement with the flange of the other side wall, and a spur carried by said cross brace for engaging the insole of the shoe and securing the form in the shoe.
45. 5. In a hollow toe form adapted to be inserted in the toe of a shoe and having side walls which terminate in inwardly projecting flanges, a cross brace connecting said walls, the brace being pivotally mounted upon the flange of one wall and having a sliding engagement with the flange of the other side wall, the pivotal movement of the cross brace causing the expansion or contraction of the side walls, and a spur carried by said cross brace for engaging the insole of the shoe and securing the form in the shoe with the side walls in the desired position.
55. 6. In a hollow toe form adapted to be inserted in the toe of a shoe and having side walls which terminate in flanges, one of said flanges having a slot therein, a cross brace connecting the side walls, the brace being pivotally joined to the unslotted flange and having a sliding engagement with the slot in the other flange, and a spur carried by said

cross brace for engaging the insole of the shoe and securing the form therein.

7. In a hollow toe form adapted to be inserted in the toe of a shoe and having side walls which terminate in flanges, one of said flanges having a slot therein, a cross brace connecting the side walls, the brace being pivotally joined to the unslotted flange and carrying means which have a sliding engagement with the slot in the other flange, such means constituting a spur which engages the insole of the shoe and secures the form therein.

8. In a hollow toe form adapted to be inserted in the toe of a shoe and having side walls which terminate in flanges, one of said flanges having a slot therein, a cross brace connecting the side walls, the brace being pivotally joined to the unslotted flange and terminating in a post which has a sliding engagement with the slot and which engages the insole of the shoe to secure the form therein.

9. In a hollow toe form adapted to be inserted in the toe of a shoe and having side walls which terminate in flanges, one of said flanges having a hole therein and the other having an arcuate slot therein, a cross brace connecting the side walls and including a post which enters the hole in one flange, and a second post which enters the slot in the other flange whereby the pivotal movement of the brace about the hole in one flange causes the second post to reciprocate in the slot and thus expand or contract the side walls, said second post being pointed at its tip to engage the insole of the shoe and secure the form therein.

10. In a hollow toe form adapted to be inserted in the toe of a shoe and having side walls which terminate in flanges, one of said flanges having a hole therein and the other having an arcuate slot therein, a cross brace connecting the side walls and including a post which enters the hole in one flange, and a second post which enters the slot in the other flange whereby the pivotal movement of the brace about the hole in one flange causes the second post to reciprocate in the slot and thus expand or contract the side walls, one of said posts being pointed at its tip to engage the insole of the shoe and secure the form therein.

Signed by me at Auburn, N. Y., this 7th day of June, 1929.
